STEAM CONTROLLING SYSTEM

Arthur Luth, Astoria, N. Y.

Application September 10, 1932, Serial No. 632,554

8 Claims. (Cl. 137—79)

This invention relates to steam heating systems and more particularly to steam heating systems which are supplied with steam at relatively high pressures and are automatic in their operation.

One object of the present invention is to improve the construction and mode of operation of steam heating systems, particularly of the type in which the source of supply is steam at appreciably higher pressures than is practicable for use in the radiating units and to provide mechanism which will effect a highly economical distribution of steam in sufficient volume to maintain any desired temperature in the areas affected by the radiating units.

A feature of the invention resides in a novel arrangement of parts whereby steam from a high pressure source is introduced at high pressure in rapidly intermittent pulsations into a low pressure system or branch which includes the heating units, the intermittency of the pulsations being determined by the building up of pressure to a predetermined point in the low pressure system.

A further feature of the invention resides in a novel arrangement of parts whereby the entire system after having been set in operation, will continue automatically so long as steam is supplied at high pressure to the system.

A further feature of the invention resides in a novel combination of pressure and temperature operated mechanisms for controlling the supply of steam from a high pressure supply to a low pressure distributing system.

A further feature of the invention resides in a novel construction and arrangement of parts whereby the entire system may be cut out of operation by a temperature control mechanism should an unexpected rise occur in atmosphere temperature to a point where the predetermined operating pressure of the low pressure branch would maintain too high a temperature in the area being heated by the system.

Still a further feature of the invention resides in a novel heating system wherein vacuum pumps, or other vacuum producing machinery, reducing valves and traps commonly employed and necessary to the successful operation of large installations, are dispensed with.

Still a further feature of the invention resides in a novel heating system in which an even distribution of steam throughout the area to be heated, is had.

Other features of the invention relate to certain novel and improved constructions, arrangements and combinations of parts hereinafter de-

scribed and particularly pointed out in the claims, the advantages of which will be readily understood and appreciated by those skilled in the art to which the invention pertains.

The invention will be clearly understood from the accompanying drawings illustrating the invention in a preferred form and the following detailed description of the constructions therein shown.

In the drawings:

Figure 1 is a fragmentary vertical sectional view of a building, illustrating a steam heating system constructed in accordance with the present invention.

Figure 2 is an enlarged view in elevation, partly in section of the control portion of the system,

Figure 3 is a view in end elevation of one of the control elements of the system,

Figure 4 is a sectional view on an enlarged scale, taken on the line 4—4 of Figure 3,

Figure 5 is a sectional view on an enlarged scale taken on the line 5—5 of Figure 3, and;

Figure 6 is a view of a portion of the operating mechanism of one of the control devices, the parts being shown in disassembled positions.

While the system of the present invention is capable of use in connection with any type of steam supply, I have chosen to illustrate it as employed in connection with a so-called commercial steam system in which steam is generated at any suitable central point and distributed at high pressure through street mains from which it is taken off for use. In the accompanying drawings, such a street main is designated by the reference numeral 10 and leading therefrom into a building 11, there is a feeder pipe 12 terminating in an automatically operating control valve 13, the specific construction of which will be hereinafter described. This portion of the system will be hereinafter referred to as the high pressure branch.

Leading from the control valve 13, there is a pipe line 14 terminating in a main riser 15 having branches 16 from which extend risers 17 arranged to supply steam to the heating units 18, herein illustrated as radiators of a conventional type. The several heating units 18 are connected by pipes 19 with a condensate line 20 terminating in a preheater 21 from which a discharge pipe 22 leads to a sewer or drain 23. This portion of the system will be hereinafter referred to as the low pressure branch.

Leading from the high pressure branch 12 as at 24 there is a pipe 25 which terminates as at 26 in the low pressure branch of the system and this

portion of the system will be hereinafter referred to as the intermediate pressure branch.

The automatically operating control valve 13 hereinbefore referred to is shown in detail in Figure 2 and it comprises a valve housing 21 having two seats 28 and 29 engaged respectively by valves 30 and 31 which are carried by a valve stem 32 which projects from the housing 21 and is connected to a yoke or similar member 33 mounted in a suitable housing 34 and secured to the upper face of a diaphragm 35. The lower side of the housing 34 is connected by means of a pipe 36 with the intermediate pressure branch 25 of the system as at 37.

This automatically operating control valve 13 is of the balanced inverted type, and by examination of Figure 2 of the drawings, it will be apparent that pressure upon the under side of the diaphragm 35 will operate to unseat the valves 30 and 31 and discharge steam from the high pressure branch 12 directly into the low pressure branch 14 at approximately the pressure of steam in the high pressure branch. The steam for operating said diaphragm 35 is obtained from the intermediate pressure branch and the desired pressure in this branch of the system is maintained by a suitable valve 38. A pivoted lever 39, carrying a weight 40, operates to move the diaphragm to move the valves 30 and 31 to seat engaging position thus cutting off the discharge of steam from the high pressure branch to the low pressure branch, this lever becoming operative when the pressure in the intermediate pressure branch is suitably reduced as will now be described.

The reference character 41 designates a pressure operated unit which as illustrated in Figures 4 and 5, comprises a housing 42 having one end closed by a cap 43 through which leads a pipe 44 which is connected at its other end to the low pressure branch as at 47. The cap 43 may serve to secure a diaphragm 48 in position and this diaphragm carries an operating button 49 which engages the nose 50 of a lever 51 pivotally mounted as at 52 in the housing 42. A spring 42' is interposed between the outer face of the diaphragm 48 and the cap 43. This lever 51 has a long arm 53 terminating in a hooked end 54 and is slotted as at 55, the slot being bridged by a pin 56 which may if desired have a roller mounted thereon. The nose 50 of the lever 51 is maintained in engagement with the operating button 49 of the diaphragm 48 by a spring 55' connected at one end to the hooked end 54 of the lever 51 and at the other end to a bolt 56' having threaded thereon a nut 57 by means of which the tension of the spring 55' may be adjusted.

Pivotally mounted as at 58 in the housing 42, there is a rocking lever 59 and this lever 59 carries a projecting stud 60 which extends through the housing as best illustrated in Figure 4. The lever is illustrated in dash lines in Figure 4 in one of its positions and in Figure 5 in its other position, in which latter position its left hand end is elevated, thus elevating the stud 60 as will be apparent by comparison of Figures 3 and 4. The lever 59 is held in the position in which it is shown in Figure 4 by the trigger 61 pivotally connected to the lever by links 62. The lower end of the trigger 61 is provided with a cam face 63 which terminates at its upper end in a notch 64, and connected to said trigger at one of its ends as at 65 there is a spring 66 the other end of which is connected to a pin or the like 67 carried by the housing 42.

By the construction just described, it will be

obvious that when the parts are in the position in which they are shown in Figure 4, the stud 60 will be held in its lower position by reason of the engagement of the cross-pin 56 in the notch 64. When, however, the diaphragm 48 rocks the lever 51 to the position in which it is shown in Figure 5, the spring 66 causes the cam face 63 to ride the cross-pin 56. The spring 66 in pulling trigger 61 to the right in Figure 5, causes a vertical movement of the trigger 61 in said figure which 10 vertical movement acts to rock the left hand end of the lever 59 upwardly to raise the pin 60. On the other hand, as the spring 55' raises the lever 53, the cross-pin 56 riding the bottom edge of the notch 64, exerts a downward pull upon the 15 trigger 61 which rocks the lever 59, in the opposite direction to lower the pin 60.

The reference character 70 designates a valve interposed in the intermediate pressure line 25, said valve being mounted on the housing 42 of the element 41. As best illustrated in Figure 4, this valve 70 comprises a housing having a seat 71 engaged by a valve member 72 to close the valve. The valve member 72 has a valve stem 73 provided with a socket 74 in which is mounted a 25 plunger 75 between which and the closed end wall of the socket 74 there is a cushion spring 76. This plunger 75 rests upon the stud 60 of the lever 59. The valve 72 is held on its seat by pressure from the high pressure branch and a 30 spring 77 and when closed prevents escape of pressure in the intermediate pressure branch, and when moved from its seat, permits the intermediate pressure branch to discharge directly into the low pressure branch 14.

As thus far described the apparatus operates as follows:

Assuming that the apparatus contains no steam and is to be started from the zero (0) point. The master valve 95 is opened and steam at the high 40 pressure carried in the street main 10 is introduced directly into the intermediate pressure branch 25. At this time, the valve 13 will be closed because of lack of pressure in the intermediate pressure branch 25 and the several parts 45 of the pressure operated unit 41 will occupy the positions in which they are illustrated in Figure 4, the valve 72 being closed.

The steam entering the intermediate pressure branch immediately builds up pressure therein 50 since there is no escape provided for this steam in the intermediate pressure branch. When the pressure in the intermediate pressure branch becomes sufficient to overcome the weight 40, the diaphragm 35 operates to lift said weight and move the valve 13 to its open position. Immediately the valve 13 opens there is a rush of steam at high pressure directly into the low pressure branch, the steam passing clear to the furthermost portion of the low pressure branch. The pressure in the low pressure branch immediately begins to build up and when it reaches the pre-determined value for which the spring 55' is set said pressure operates the diaphragm 48 to rock the lever 51 and elevate the stud 60 as heretofore described moving the valve 72 to open position to exhaust the intermediate pressure branch 25 into the low pressure branch. Reduction of pressure in the intermediate pressure branch permits the weight 40 to move the valve 13 to closed position thus shutting off the discharge of steam from the high pressure branch to the low pressure branch. Immediately the supply of high pressure steam from the high pressure branch is cut off, the pressure within the low pressure branch be- 75

gins to fall and the spring 55' immediately restores the several parts of the pressure operated unit 41 to that position shown in Figure 4 in which position, the valve 72 will be closed and pressure begins again to build up in the intermediate pressure branch to again operate the diaphragm 35 to open the valve 13 and effect another introduction of steam at high pressure into the low pressure branch which again operates as described to close off the valve 13.

The above cycle of operation takes but a few seconds to complete, the periodicity of the cycle depending in part upon temperature and in part upon adjustments of the various parts such as the tension of the spring 55' and the position of the weight 40 relative to the end of the lever 39, but even though the periodicity of each cycle is very short the several operations of each cycle take place exactly as described and the valve 13 is intermittently operated to introduce steam at high pressure directly into the low pressure branch of the system in impulses of extremely short duration. As the operation progresses and the temperature of the area affected by the several heating units 18 rises, the pressure in the low pressure branch will not fall as rapidly and the intervals at which the above described cycles are effected will naturally be of longer duration but in any event, the adjustments will be such that the desired temperature will be maintained.

From the foregoing description, it will be obvious that the present invention provides a steam heating system in which steam is distributed intermittently in sufficient quantities to maintain desired temperatures and that all electrical and temperature operated and controlled devices have been eliminated, the system being automatically controlled and operated by pressure alone.

While as above stated, the system is capable of operation without the aid of temperature controls, I may, as an additional control, provide temperature controlled means for rendering the system operative and inoperative and this temperature control is preferably wholly independent of the pressure control apparatus.

While the operation of the temperature control device may be effected or controlled by variations of temperature at any given point or location, I prefer to employ the condensate temperature and outside or atmosphere temperature in combination and in such a manner that each will aid the other in the control of the system.

To the attainment of these ends, I provide a valve 100, preferably of the double balanced type. This valve 100 is located as illustrated, in the low pressure branch of the system and is so constructed and arranged that under normal operating temperatures, the valve will be maintained open to permit of the flow of steam therethrough to that part of the low pressure system beyond the valve 100 and will close to prevent the flow of steam to the low pressure branch beyond the valve 100 when predetermined high temperatures at pre-determined locations in the system, are reached.

The valve 100 is preferably of a conventional type which will be operated in one direction, (preferably opened) by a spring and closed by an expansible fluid which exerts a force upon the valve stem 101.

The expansible fluid is carried in conduits 102 and 103 preferably of conventional type and each tube has a thermal unit they being herein designated 104 and 105 respectively.

In the present embodiment of the invention, the

thermal element 104 is placed in the condensate line 20 in such a manner that it will be directly affected by the temperature of the condensate in said line, the thermal unit 105 being so located that it is directly affected by outside temperatures.

By the arrangement described above should the temperature of the condensate rise or the outside temperature rise, or both, the thermal units will operate to effect an expansion of the fluid in the conduits 102 and 103 and operate to partially or completely close the valve 100 depending upon the rise of temperature. The valve 100 and its controls being independent of the valve 27, the valve 27 functions as described, the supply of steam in front of the valve 100 being at all times the same, the valve 100, however, controlling by its position, the quantity of steam distributed through the low pressure branch of the system.

Thus it will be apparent that when the temperature control is functioning, steam at substantially street main pressure is circulated through the low pressure branch of the system when the valve 100 is completely open and that even though steam at full street main pressure is introduced into the low pressure branch of the system, when the valve 100 is partially closed, a correspondingly lesser pressure will be circulated through the low pressure branch.

From the foregoing, it will be readily apparent that the present invention provides a new and improved system of steam distribution which is highly efficient in operation and which will maintain desired temperatures with minimum steam consumption.

While the invention has been herein illustrated in its preferred form, it is to be understood that it is not to be limited to the specific construction in which it is shown particularly with respect to the specific types of pressure and thermal devices herein illustrated since such devices may be employed in various forms within the scope of the present invention.

Having thus described the invention, what is claimed as new and what it is desired to secure by Letters Patent of the United States, is:—

1. A steam controlling system including a high pressure branch, a low pressure branch and an intermediate pressure branch, a valve for controlling the flow of steam from the high pressure branch to the low pressure branch at the pressure present in said high pressure branch, means operated by fluctuations of pressure in the intermediate pressure branch for opening and closing said valve, and pressure operated means for producing fluctuations in pressure in said intermediate pressure branch.

2. A steam controlling system including a high pressure branch, a low pressure branch and an intermediate pressure branch, a valve for controlling the flow of high pressure steam from the high pressure branch to the low pressure branch at the pressure in the high pressure branch, means operated by fluctuations of pressure in the intermediate pressure branch for opening and closing said valve, and means operated by a pre-determined pressure in the low pressure branch for producing fluctuations in pressure in the intermediate pressure branch.

3. A steam controlling system including a high pressure branch, a low pressure branch and an intermediate pressure branch, a valve for controlling the flow of high pressure steam from the high pressure branch to the low pressure branch at the pressure in the high pressure branch,

- means operated by fluctuations of pressure in the intermediate pressure branch for opening and closing said valve, and means operated by a pre-determined pressure in the low pressure branch 5 for producing fluctuations in pressure in the intermediate pressure branch and including means for discharging pressure from the intermediate pressure branch, into the low pressure branch.
- 10 4. A steam controlling system including a high pressure branch, a low pressure branch and an intermediate pressure branch connecting the high pressure branch with the low pressure branch, a valve in said intermediate pressure branch to alternately establish and cut off communication 15 between the intermediate pressure branch and the low pressure branch to produce fluctuations of pressure in the intermediate pressure branch, a valve operated by the fluctuations in pressure in 20 the intermediate pressure branch for establishing and cutting off direct communication between the high pressure branch and the low pressure branch and for admitting steam to the low pressure branch at the pressure of the high pressure 25 branch, and pressure operated means for operating the valve in intermediate pressure branch.
5. A steam controlling system including a high pressure branch, a low pressure branch and an intermediate pressure branch connecting the 30 high pressure branch with the low pressure branch, a valve in said intermediate pressure branch to alternately establish and cut off communication between the intermediate pressure branch and the low pressure branch to produce fluctuations of pressure in the intermediate pressure 35 branch, a valve operated by the fluctuations in pressure in the intermediate pressure branch for establishing and cutting off direct communication between the high pressure branch and the low pressure branch to admit steam at the pressure 40 of the high pressure branch to the low pressure branch, and pressure operated means for operating the valve in intermediate pressure branch, said last mentioned means being operated by pre-determined pressure in the low pressure 45 branch.
6. In a steam controlling system, a high pressure branch, a low pressure branch and an intermediate pressure branch, said intermediate pressure branch having communication with both 50 the high and low pressure branches, a valve separating the low pressure branch from the high pressure branch, means tending to hold said valve

in closed position, means operable by pressure in the intermediate pressure branch for moving said valve to open position upon presence of a predetermined pressure in the intermediate pressure branch, and means operated by a predetermined pressure in the low pressure branch for releasing the pressure in the intermediate pressure branch and permitting the valve between the high pressure branch and the low pressure branch to move to closed position.

7. In a steam heating system, a high pressure branch, a low pressure branch and an intermediate pressure branch, a valve interposed between the high pressure branch and the low pressure branch, said valve serving to establish communication between the high pressure branch and the low pressure branch when the valve is open and to cut off such communication when the valve is closed, mechanically operated means for moving said valve normally to its closed position, pressure operated means operated by the building up of a predetermined pressure in the intermediate pressure branch for moving said valve to its open position, and means responsive to pressure in the low pressure branch of the system for effecting a reduction of pressure in the intermediate pressure branch to permit movement of the valve to its closed position by said mechanically operated means.

8. In a steam heating system, a high pressure steam supply line, a low pressure branch, a valve interposed between the supply line and the low pressure branch, said valve adapted to admit steam to the low pressure branch from the supply line at a pressure not lower than the pressure present in the supply line, and means for intermittently operating said valve, said last mentioned means including an intermediate pressure branch connected to both the supply line and the low pressure branch, pressure responsive means actuated by a predetermined pressure in the intermediate pressure branch for opening the valve between the supply line and the low pressure branch to admit a charge of steam at a pressure not lower than the pressure of the supply line to the low pressure branch, means responsive to a predetermined pressure in the low pressure branch for effecting a reduction of pressure in the intermediate pressure branch, and means for closing the valve between the supply line and the low pressure branch upon reduction of pressure in the intermediate pressure branch.

ARTHUR LUTH.
